United States Patent Office

Des. 215,347
Patented Sept. 23, 1969

215,347

TRASH RECEPTACLE OR THE LIKE

Raymond J. Mangold, Montville, and Clayton S. Myers,
Fanwood, N.J., assignors, by mesne assignments, to
Continental Manufacturing Company, St. Louis, Mo.,
a corporation

Filed Oct. 4, 1968, Ser. No. 13,846

Term of patent 14 years

Int. Cl. D7—06

U.S. Cl. D49—35

FIG. 3

FIG. 4

FIG. 5

FIG. 6

FIGURE 1 is an isometric view of a receptacle showing our design;

FIGURE 2 is an expanded view of the receptacle of FIGURE 1, showing its three component parts;

FIGURE 3 is a side plan view of the receptacle of FIGURE 1;

FIGURE 4 is a top plan view of the receptacle of FIGURE 1;

FIGURE 5 is a bottom plan view of the receptacle of FIGURE 1; and

FIGURE 6 is a central cross-sectional view taken through the indented handle parts of the receptacle of FIGURE 1.

We claim:

The ornamental design for a trash receptacle or the like, substantially as shown.
